DAVID M. DEMAREST, OF NEW YORK, N. Y., JOHN J. DEMAREST, OF JERSEY CITY, AND NICHOLAS H. JORALEMON, OF HOBOKEN, NEW JERSEY.

Design No. 4,216, dated July 12, 1870.

DESIGN FOR A TRADE-MARK.

The Schedule referred to in these Letters Patent and making part of the same

To all whom it may concern:

Be it known that we, DAVID M. DEMAREST, of New York, in the State of New York, JOHN J. DEMAREST, of Jersey City, and NICHOLAS H. JORALEMON, of the city of Hoboken, in the State of New Jersey, have invented and produced a new and original Design for a Trade-Mark, of which the following is a specification.

Our design may be printed or embossed upon a card or label, or the same may be printed, painted, stamped, burned, cut, or in any other way produced at and upon the box or paper containing the manufactured article.

Our design consists of a line, A, forming an oval, having in the center a picture of a "fish," B, and below the figure of the fish, in letters, the words, "trademark."

We claim as our invention—

The design for a trade-mark, as described and shown.

DAVID M. DEMAREST.
NICHOLS. H. JORALEMON.
JOHN. J. DEMAREST.
